ALEXANDER LAWRENCE,
INVENTOR,

By ATTORNEY

UNITED STATES PATENT OFFICE

156,976

GROOMING RACK

Alexander Lawrence, New York, N. Y.

Application April 6, 1948, Serial No. 145,562

Term of patent 3½ years

(Cl. D33—3)

To all whom it may concern:

Be it known that I, Alexander Lawrence, a citizen of the United States of America, residing in New York city, county of New York, and State of New York, have invented a new, original, and ornamental Design for a Grooming Rack, of which the following is a specification, reference being had to the accompanying drawing, forming part thereof, wherein:

I claim:

The ornamental design for a grooming rack, substantially as shown.

ALEXANDER LAWRENCE.
